TAPE DISPENSER

William Macowski, Caldwell, N.J., assignor to Ketcham &
McDougall, Inc., Roseland, N.J.

Filed May 14, 1971, Ser. No. 143,741

Term of patent 14 years

Int. Cl. D19—02

U.S. Cl. D74—1

FIG. 1

FIG. 2

FIG. 3

FIG. 4

FIG. 5

FIG. 1 is a perspective view of a tape dispenser embodying my new design;

FIG. 2 is a top plan view of the tape dispenser shown in FIG. 1;

FIG. 3 is a front elevational view;

FIG. 4 is a side elevational view, the opposite side being a mirror image thereof; and

FIG. 5 is a rear elevational view thereof.

I claim:

The ornamental design for a tape dispenser, as shown
